UNITED STATES PATENT OFFICE

SIMON COOPER, OF BROOKLYN, NEW YORK

ELECTRICAL SOSTENUTO PIANO

Application filed March 25, 1927. Serial No. 178,204.

This invention relates to electrical sostenuto pianos; particularly of the type described in United States Letters Patent to me No. 1,598,056, August 31, 1926, in that electro-magnetic means are employed for the 5 sostenuto and these means are operated by current pulsators directly connected to the strings. The operation of each such pulsator, in the patented arrangement, depends upon the relative motion between the two electrodes, one of which is directly connected with the string which it controls; and, according to said arrangement, various adjustments of the pulsators, as regards their 10 relation to the strings, the weight and inertia of the electrodes, etc., are depended on to effect a proper synchronization of the pulsators with the strings.

Said adjustments necessarily are difficult, 20 require considerable skill and must be determined to a large extent empirically.

One of the objects of the present invention is to provide a method of and means for insuring dependable sostenuto without trouble- 25 some empirical adjustments.

Again, if the vibration of a string is to be sustained to give sostenuto, the intermittent "pulls" of the magnet on the string must be timed to agree with the natural vibratory 30 movements of the string toward the magnet. In this connection, it must be remembered that a piano string, even in the bass scale, is vibrating quite fast; and this speed of vibration reaches a very high frequency at the 35 treble scale of strings. Now, all previous pulsators have two electrodes which make contact with each other or have between them some conductor such as carbon pencils, balls or granules, and current flowing 40 through the pulsator or transmitter is caused to fluctuate by the varying pressure of contact of the electrodes on each other or on the conducting medium between them. All commercial pulsators have one of the electrodes 45 suspended by means of a diaphragm, and the other electrode fixed as by resting upon the electrode suspended by the diaphragm. This suspended diaphragm will have its natural period or frequency of vibration, yet it will 50 be readily understood that unless this natural

frequency is equal to or a sub-multiple of the frequency of the string vibration, there will be no possibility of obtaining current pulsations which match properly the string vibration.

Another object is to provide a method of and means for insuring dependable sostenuto, as above; and by the use of a pulsator vibrating at the rate, or at a rate corresponding to a sub-multiple, of the rate of free vibration of the string, thereby to utilize my discovery that a pulsator so vibrating, provided another difficulty is disposed of, is capable of true sostenuto.

Accordingly, a further object is to provide a method and means, as already stated, and also a method and means of taking care of the difficulty just referred to, the distortive or destructive effect of a part of the pulsator or its support vibrating according to its own 70 natural period of vibration.

These various objects of the invention are attained by making the pulsator in effect "non-resonant" as regards the string. This I may accomplish in a commercial way by 75 attaching one of the electrodes of the pulsator to the string by a rigid mechanical connection, as in said patent, and by supporting the other electrode on or by means of a non-resonant medium. Preferably, one of said 80 electrodes is relatively massive, so that inertia is a factor; and, consequently, it is also preferred to have the electrode supported in the non-resonant medium the relatively massive one.

I find that when a pulsator has one of its electrodes non-resonant, or supported by a non-resonant medium, and the other electrode mechanically connected to the string, all difficulties are overcome, and the pulsator is 90 synchronized for sostenuto while vibrating at the rate, or at a rate corresponding to a sub-multiple of the rate, of free vibration of the associated string.

I find also that then, the transverse movement of the string, even where the connection is made at a point nearer one bridge support than the other to hold down interference with the natural motion of the string, vibrates the pulsator to cause relative motion of the elec- 100

trodes which may be depended on for sostenuto synchronization, and true sostenuto.

It is true, of course, that during the rapid vibration of the fixed or string-connected electrode and say the granular carbon mass between the electrodes, the fixed electrode moves with each motion of the string toward and from the non-resonant electrode, resulting in a number of rapid impacts on the latter. On the other hand, the non-resonant electrode is on a sluggish non-resonant mount or support; and the motion of the non-resonant electrode, relative to the other electrode and the granular filling, I find, is comparatively slight, particularly on the higher pitched note strings; occurs a less number of times per second, and occurs at a rate corresponding to a sub-multiple of the rate of free vibration of the string. The action might be illustrated by considering the non-resonant electrode as an anvil on which light hammer blows are successively struck, the inertia of the anvil preventing a displacement of itself as quickly or as often as the blow is struck.

Further, I find that such displacement occurs, with an accompanying current pulsation, and an accompanying pull on the string by the magnet, after every so many string vibrations, and each such pull on the string is exerted only while the string is moving toward the magnet. This is attained dependable sostenuto, and yet troublesome empirical adjustment of the pulsator is not a factor.

At the same time, I find that since one of the electrodes at least is not supported by a means or medium capable of exhibiting its own natural period of vibration, no deleterious variations in the current pulsations occur, and so true sostenuto, also, is attained.

Another object of the present invention is to overcome a serious trouble in previous microphones as attempted to be used for electrical sostenuto in pianos. This trouble arises from the disintegration of the contact surfaces of the carbon elements due to mechanical abrasion and arising as a result of incandescence or even arcing at or across the points of contact.

According to the present invention, I provide, in a pulsator having a non-resonant mount for one of the electrodes, a collection of carbon granules or the like arranged or retained in such manner as to offer what may be termed self-renewing contact surfaces or points.

Another object of the present invention is to provide a method of arranging the connection between a piano string and one of the electrodes of the controller or pulsator for that string, whereby interference with the natural motion of the string will be held down considerably, and at the same time the pulsator will be operated for true sostenuto according to the invention. I have discovered that such operation may be had when

said connection, as a mechanical one, is made at the string very close to one of the bridge supports of the latter, or even at a non-singing portion of the string; and, also, that the pulsator will function usefully according to 70 the invention when attached to the sounding board, and, in some instances when attached to the piano frame.

Still another object of the invention is to provide an electrical attachment for a piano string having parts so connected to and associated with the string that the electrical sostenuto may act primarily or accentuatingly in regard to a tone made up of a desired combination of the fundamental and its 80 harmonics.

In the accompanying drawings, to which reference will now be had, several different illustrative forms of the invention are shown; but these forms are, as just stated, of course 85 merely illustrative, and not to be taken as in any sense defining or limiting the invention itself.

Fig. 1 is a diagrammatic view illustrating one form of circuit and possible relations of 90 the actuating magnet and controlling pulsator to a piano string.

Fig. 2 is a longitudinal vertical section of the form of pulsator shown in Fig. 1, illustrating also a type of auxiliary support. 95

Fig. 3 shows the pulsator of Fig. 2 in perspective.

Fig. 4 is view similar to Fig. 2, but showing a different form of pulsator and a different support therefor. 100

Fig. 5 shows the pulsator of Fig. 4 in perspective.

Fig. 6 shows partly in top plan and partly in section still another form of pulsator according to the invention. 105

Fig. 7 shows in vertical section, still another form.

Fig. 8 is a sectional view of still another form.

In Fig. 1, one of the piano strings is indicated at 10, stretched over the bridge pieces 11, 12. 13 indicates the electro-magnet for vibrating the string and 14 the pulsator for controlling said magnet, said pulsator being located in a circuit with the magnet, which circuit includes a suitable source of energy 15 and a switch 16 operated by the piano key 17.

The pulsator comprises in each instance a pair of cooperating electrodes 18 and 19 with an interposed mass 20 of carbon granules or the like. One of these electrodes 18 is rigidly connected with the piano string by means consisting in the case of Figs. 1, 2 and 3, of a bar or rod 21 shown as having a forked end 22 which is forced over the piano string, said bar having secured thereto a sleeve 23 of fibre or the like in which the electrode is affixed. The companion electrode 19 is loosely contained in an envelope 24 of felt, wool yarn 130

or the like which fits inside the sleeve or thimble 23 so as to hold the electrode in proper relation to the granular mass, a wrapping of yarn 25 being provided to hold the outer 5 portion of the envelope to the supporting bar and a pad 26 of felt being shown as interposed between the outer end of the envelope and the bar as a further cushioning medium. The non-resonant electrode 19 is relatively 10 heavy; in other words, is of sufficient mass to give it such inertia that it will operate in effect as an "anvil" for the lighter, directly actuated "hammer" electrode, and being supported as it is in a non-resonant envelope, 15 its motion, relative to the other electrode, is slight and of less frequency.

The electromagnet is supported so as to operate directly on the string, which is made susceptible to magnetic attraction, and the 20 effect of this pulsator is to keep the force of the electromagnet in phase with the motion of the string, in the sense that each pull of the magnet on the string occurs while the string is moving toward the magnet, so that 25 the vibration of the string is sustained and the string is caused to emit its true musical tone.

The outer end of the pulsator may be supported as by suspending it with a cable 27 30 from a bar or bridge 28. Then it is possible to raise or lower the free end of the pulsator without changing its point of connection with the piano string. The raising or lowering of the connection tips up or down the free end 35 of the pulsator and correspondingly affects the conductivity of the granular mass. These adjustments obviously will have an effect on the operation of the pulsator and may be used where some adjustment is necessary to bring 40 the pulsator into synchronous relation with the string.

Figs. 4 and 5 illustrate a somewhat simplified form of pulsator in which both the electrodes are encased in a common non-resonant 45 envelope 32 of felt or the like and the string-vibrated electrode is connected with the string by an arm 33 directly secured thereto as by means of a screw 34 and having a notched end as before to clamp on the string. 50 The screw 34 may be used as the terminal screw for the vibrated electrode and the non-resonant electrode may have a terminal screw 35, these being similar to the terminal screws provided in the first form of the invention.

In the form of the invention disclosed in Fig. 6, there is a sleeve or thimble 36 similar to the sleeve 23 used in the first form shown, except that in this instance it encloses both 60 electrodes, the non-resonant support for the heavier electrode being provided in this case by a loose wrapping 37 of yarn or the like interposed between the anvil electrode and the surrounding sleeve or shell. Another feature 65 of this form is that the arm 38 which is

notched to connect with the string is formed as an integral extension of the shell.

The form of the invention shown in Fig. 7 differs from the form disclosed in Fig. 2 principally in that a pad 39 of felt or other 70 non-resonant material is interposed between both electrodes and the supporting bar 21.

The form of pulsator shown in Fig. 8 has a thimble or shell 28, of fibre or the like, sleeves both electrodes as in Figs. 2, 6 and 7; but in the present case the more massive electrode 19' is connected to the piano string as by screw-pin 29, shaped to present at its free end a flat blade notched as indicated at 29a. The screw-pin may carry a nut (not shown) 80 to take the end of a wire in the circuit containing current source 15; the other electrode 18' carrying a screw 18a for a similar connection. The non-resonant envelope is indicated at 30. 85

One of the important features of the present invention, graphically shown in Fig. 8 at 31, and preferably present in all forms of the invention, is that the body of carbonaceous or other suitable granular conducting material is loosely confined between the electrodes so as to be free to move for the purpose 90 of automatically and from time to time presenting new conducting surfaces and new contacting points. 95

The pulsator is preferably attached to the string at a point where the "loop" of the freely vibrating string will assist in causing the magnet to attract the string at times when the string is moving toward the magnet. 100 This point of attachment may be determined by experiment and is usually found to be somewhere about the upper supporting bridge.

During vibration of the piano string, motion is imparted to the fixed electrode, the granular conducting mass, and, in a retarded fashion, due to the interposition of the non-resonant element, to the electrodes supported on said elements; while, due also to the presence of said element, true sostenuto is not at all interfered with by any part of the pulsator or its support vibrating in accordance with its own natural frequency of vibration, at least so far as the ear can determine. 105 110 115

At the same time, the relative motions of the electrodes result in alternate compression and release of the carbon granules or pellets as between themselves and the faces 120 of the electrodes, producing variations in circuit resistance proportional to and in time with the vibrations of the string; and the magnet, being under control of the pulsator, is actuated accordingly to maintain 125 the string in vibration so long as the controlling switch is closed.

Such actuation of the pulsator, where the carbon granules are not immovably confined, results in a slow circulation of the 130

granules in the space between the electrodes. As the amplitude of vibration increases or the number of vibrations per second is greater, or both, circulatory movement of the granules is more pronounced. If the amplitude of vibration is small, even though the number of vibrations per second is quite high, the circulatory movement is comparatively slow. Under both conditions, however, the relation of the granules to each other and the relation of the granules in contact with the electrodes follows a progressive action, automatically renewing the contact surfaces whenever the piano string is in vibration.

I have discovered that it is highly desirable, if not essential to synchronize the energization of the magnet with the motion of the string, in such wise that the magnet is energized at a moment which will attract the string at a particular point in its path of vibration, so that the vibratile formation of the string which must exist to sound the note and the harmonics desired is not disturbed by the application of the magnetic force. In sounding a piano string, the requirement is that a fundamental and certain harmonics of that fundamental be audible, and that certain other fundamentals which are unharmonic with the first fundamental be deadened. In some piano actions, for instance, the hammer (indicated at H in Fig. 1) is caused to strike the string at one-seventh or one-ninth of its length, such a blow preventing the formation of a node at the point struck and so damping or destroying the seventh or ninth harmonic. It should be pointed out, as my experiments apparently demonstrate, that while the magnet exerts a small magnetic pluck on the string, the magnetic attraction is not confined to a point but is rather stretched over a zone in the length of the string. Also, the magnetic attraction is not staccato or in the nature of a blow, but rather is a force wave, rising from what can be termed a zero point to a maximum, and this wave coincides with the motion of the string toward the magnet. Therefore, according to the present invention, the magnet is so located, and it may thus be empirically located without great trouble, that the magnetic pluck occurs at such a zone along the length of the string as to sound only such fundamentals as are essential to best musical results, that is, to sound the fundamental and such harmonics as are desired while holding down the undesirable harmonics.

I find that the structure shown in Fig. 7 is particularly desirable where it is wished to secure a more mellow and less sharp tone than that produced with say the form of Fig. 2. In all the forms shown, however, the non-resonant method of supporting one of the electrodes enables said electrode to adjust it-

self to a periodic vibration timed to, and a sub-multiple of, the natural rate of vibration of the string, as already pointed out; which in turn permits the string-connected electrode to vibrate without impeding or interfering with the natural vibration of the string.

Inasmuch as many changes could be made in the above constructions, and many apparently widely different embodiments of my invention could be made without departing from the scope thereof, it is intended that all matter contained in the above description or shown in the accompanying drawings shall be interpreted as illustrative and not in a limiting sense.

It is also to be understood that the language contained in the following claims is intended to cover all the generic and specific features of the invention herein described and all statements of the scope of the invention which, as a matter of language, might be said to fall therebetween.

What I claim is:

1. In a device of the kind described, a vibratory string; a pulsator comprising an electrode rigidly connected with the string and a cooperating electrode of greater mass than the first, means for supporting the cooperating electrode in non-resonant relation to the vibratory string, and a magnet for vibrating the string controlled by said pulsator.
2. In a device of the kind described, a vibratory string, a pulsator comprising an electrode rigidly connected with the string and a cooperating electrode, means for supporting the cooperating electrode in non-resonant relation to the vibratory string, and a magnet for vibrating the string controlled by said pulsator.
3. In a device of the kind described, a vibratory string, a magnet for vibrating the same and a controller for said magnet comprising cooperating electrodes, one relatively light and rigidly connected with the vibratory string and the other relatively heavy, and means for supporting the cooperating electrode in non-resonant relation to the string.
4. In a device of the kind described, a vibratory string, a magnet for vibrating the same and a controller for said magnet including a member rigidly connected with the string, an electrode mechanically connected with said member, a cooperating electrode and a non-resonant support for said second electrode.
5. In a device of the kind described, a vibratory string, a magnet for vibrating the same and a controller for said magnet including a member rigidly connected with the string, an electrode mechanically connected with said member, a cooperating electrode and a non-resonant support of felt-like material for said second electrode.

6. In a device of the kind described, a vibratory string, a magnet for vibrating the same and a controller for said magnet including a member rigidly connected with the string, an electrode mechanically connected with said member, a cooperating electrode, and a non-resonant support for said second electrode and interposed between said electrode and the string engaging member aforesaid. 10 70
7. A pulsator for the purpose described comprising a member for rigid engagement with a vibratory string, an electrode connected with said member, a cooperating electrode, and a non-resonant support interposed between said cooperating electrode and the member aforesaid. 15 75
8. A pulsator for the purpose described comprising a member for rigid engagement with a vibratory string, an electrode rigidly fixed to said member, a cooperating electrode, and substantially non-resonant means for supporting said second electrode on said member. 20 80
9. A pulsator for the purpose described comprising a member for rigid engagement with a vibratory string, an electrode rigidly fixed to said member, a cooperating electrode, and a substantially non-resonant sleeve for supporting said second electrode on said member. 25 85
10. In a device of the kind described, a support provided with means for connecting the same with a vibratory string, a sleeve carried by said support, an electrode in said sleeve, a cooperating electrode in said sleeve, and an envelope of non-resonant material about one of said electrodes. 30 90
11. In a device of the kind described, a support provided with means for connecting the same with a vibratory string, a sleeve carried by said support, an electrode fixed in said sleeve, a second electrode of greater mass than the first, a mass of variable conductivity between the electrodes, and a non-resonant supporting medium for the electrode of greater mass. 40 95
12. In a device of the kind described, a support provided with means for connecting the same with a vibratory string, a sleeve carried by said support, an electrode fixed in said sleeve, a second electrode of greater mass than the first, a mass of variable conductivity between the electrodes, and a non-resonant supporting medium for the electrode of greater mass. 45 100
13. In an electric sostenuto piano, a vibratory string, a magnet for vibrating the same, and a pulsator in circuit with said magnet comprising an electrode rigidly connected with the string, a non-resonant element, and a cooperating electrode connected with the string through said element. 50 105
14. The herein disclosed means for producing a sostenuto effect in a vibratile string which comprises a pulsator supported directly on the vibratile string, said pulsator including spaced electrodes, means connecting one of the electrodes of said pulsator rigidly with the string, means supporting the companion electrode by a non-resonant medium and a magnet for vibrating the string controlled from said pulsator. 55 110
15. In a device of the kind described, the combination of a support provided with means for mechanically attaching the same directly to a vibratory string, a pulsator on said support including relatively movable electrodes and a mass of granular conducting material interposed between said electrodes, and means for adjusting the inclination of said support to vary the action of said electrodes on said mass. 60 115
16. In a device of the kind described, the combination of a support provided with means for mechanically attaching the same directly to a vibratory string, a pulsator on said support including relatively movable electrodes and a mass of granular conducting material interposed between said electrodes, means for non-resonantly supporting one of said electrodes on the support, and auxiliary supporting means for the pulsator adjustable to vary the action of said electrodes on said mass. 65 120
17. In a device of the kind described, the combination of a support provided with means for mechanically attaching the same directly to a vibratory string, a pulsator on said support including relatively movable electrodes and a mass of granular conducting material interposed between said electrodes, and suspensory means for a part of said support removed from its point of engagement with the string. 70 125
18. In a device of the kind described, the combination of a support provided with means for mechanically attaching the same directly to a vibratory string, a pulsator on said support including relatively movable electrodes and a mass of granular conducting material interposed between said electrodes, and means for adjustably inclining said support to the horizontal and to cooperate with said support in sustaining said pulsator opposite a predetermined point along the length of the string. 75 130
19. In a sostenuto piano, an electric controller comprising a pair of cooperating relatively movable electrodes arranged with a chamber between opposing surfaces thereof, a granular conducting body loosely confined in said chamber between said surfaces to thereby enable circulation of the individual granules to continually create fresh contact surfaces between the granules and between said granules and the electrode surfaces, a direct mechanical connection for attaching one 80 135

of the electrodes to a piano string, and non-resonant means for supporting the companion electrode from said first electrode.

20. In an electrical sostenuto device for pianos, the combination of a piano string, a pulsator having a plurality of relatively movable electrodes one of which is connected mechanically to the string, said mechanical connection engaging the string at about one 10 of the bridge supports for the string, there being a non-resonant mount for the other electrode of the pulsator.

21. The means defined in claim 14, which also includes rigid means connecting the first- 15 mentioned electrode to the string at a point at or near one of the supporting bridges to cause the magnet to act on the string to produce a predetermined musical tone, by sounding the desired fundamental and harmonics 20 only.

22. The herein disclosed process of producing a sostenuto effect while accentuating only the desired fundamental and harmonics, to obtain a predetermined musical tone, which 25 consists in magnetically plucking the string at such point as to accentuate only the desired fundamental and harmonics.

23. In an electric sostenuto piano action, the combination of a current pulsator for causing current fluctuation operated by the vibration of the string and including a plurality of relatively movable electrodes, a magnet for imparting sostenuto to the string, and means for maintaining true sostenuto and including a mount for one of the electrodes to maintain that electrode subject to the inertia of its mass for causing such fluctuation.

24. In an electric sostenuto piano action, the combination of a current pulsator operated by the vibration of the string and including a plurality of relatively movable electrodes, a magnet for imparting sostenuto to the string, and means for maintaining true sostenuto during current fluctuation of a frequency which is a sub-multiple of the frequency of vibration of the string, said means including a non-vibratory mount for one of the electrodes.

25. In an electric sostenuto piano action, the combination of a current pulsator operated by the vibration of the string and including a plurality of relatively movable electrodes, a magnet for imparting sostenuto to the string, and means for maintaining true sostenuto and including means for maintaining one of the electrodes devoid of any natural pitch of vibration.

26. In an electric sostenuto piano, a pulsator; and means for securing said pulsator to a string, said means providing a mount for the pulsator including a forked element for gripping engagement with the string.

27. In an electric sostenuto piano, a pulsator; and means for securing said pulsator to a string, said means including a support car-

rying a fork for wedgingly engaging the string and a flexible suspensory element for varying the angle of the fork from the perpendicular relative to said string.

28. In a sostenuto device for pianos, the combination of a string, a circuit, a magnet for actuating the string for sostenuto, and a pulsator including a first electrode directly vibrated by string vibration and a second electrode so massive as to be directly unaffected by string vibration.

29. In an electric sostenuto system for pianos, an electric current undulating device on a string, means for connecting said device to said string at about one of its bridge supports, and means for suspending the device from a support isolated from sympathetic vibration with the string.

30. A pulsator for purposes set forth, comprising an electrode of moderate mass, means 85 providing a direct connection of the electrode to a vibratory string; a second electrode of substantial mass, comminuted conducting material between adjacent ends of the electrodes, and non-resonant material surrounding and supporting the second electrode in relation to the first.

31. A pulsator for purposes set forth, comprising an electrode of moderate mass, means providing a practically direct mechanical connection of the electrode to a vibratory string, a second electrode of relatively greater mass, comminuted conducting material between adjacent ends of the electrodes, and a sleeve of non-resonant material surrounding and supporting the second electrode in relation to the first.

32. A pulsator for purposes set forth, comprising a supporting member having at one end means for connection to a vibratory string, a sleeve thereon, a first electrode of moderate mass held in said sleeve, a second electrode of substantial mass having a part within the sleeve, comminuted conducting material confined in the sleeve between the electrodes, and a sleeve of non-resonant material surrounding the second electrode and supporting it in relation to the first named sleeve.

33. A pulsator for purposes set forth, comprising a substantially rigid supporting member having at one end means for connection to a vibratory string, a sleeve thereon, a first electrode of moderate mass held in said sleeve, a second electrode of relatively greater mass having a part within the sleeve, comminuted conducting material confined in the sleeve between the electrodes, and a sleeve of substantially resilient, non-resonant material surrounding the second electrode and supporting it in relation to the first named sleeve.

34. A pulsator for purposes set forth, comprising a supporting member having at one end means for connection to a vibratory string, a sleeve thereon, a first electrode of

moderate mass held in said sleeve, a second electrode of substantial mass having a part within the sleeve, comminuted conducting material confined in the sleeve between the electrodes, a sleeve of non-resonant material

5 surrounding the second electrode and supporting it in relation to the first named sleeve, and non-resonant cord winding securing the non-resonant sleeve to the support.

35. A pulsator for purposes set forth, comprising a substantially rigid supporting member having at one end means for connection to a vibratory string, a sleeve thereon, a first electrode of moderate mass held in said sleeve, a second electrode of relatively greater mass having a part within the

15 sleeve, comminuted conducting material confined in the sleeve between the electrodes, and a sleeve of substantially resilient, non-resonant material surrounding the second electrode and supporting it in relation to the first named sleeve, and non-resonant cord winding securing the non-resonant sleeve to the support.

36. A pulsator for purposes set forth, comprising a supporting member having at one end means for connection to a vibratory string, a sleeve thereon, a first electrode of moderate mass held in said sleeve, a second electrode of substantial mass having a part

30 within the sleeve, comminuted conducting material confined in the sleeve between the electrodes, a sleeve of non-resonant material surrounding the second electrode and supporting it in relation to the first named sleeve, and non-resonant material interposed between the support and said sleeves.

37. A pulsator for purposes set forth, comprising a substantially rigid supporting member having at one end means for connection to a vibratory string, a sleeve thereon, a first electrode of moderate mass held in said sleeve, a second electrode of relatively greater mass having a part within the sleeve,

45 comminuted conducting material confined in the sleeve between the electrodes, a sleeve of substantially resilient, non-resonant material surrounding the second electrode and supporting it in relation to the first named sleeve, and non-resonant material interposed between the support and said sleeves.

38. A pulsator for purposes set forth, comprising a supporting sleeve, means for connecting one end of the sleeve to a vibratory string, a first electrode of moderate mass and held in the sleeve near one end thereof, a second electrode of substantial mass within the sleeve, comminuted conducting material confined in the sleeve between the electrodes, and non-resonant material supporting the second electrode in the sleeve.

39. A pulsator for purposes set forth, comprising a supporting sleeve, means for connecting one end of the sleeve to a vibratory string, a first electrode of moderate mass and

held in the sleeve near one end thereof, a second electrode of relatively greater mass within the sleeve, comminuted conducting material confined in the sleeve between the electrodes and non-resonant material supporting the second electrode in the sleeve.

70

40. A pulsator for purposes set forth, comprising a supporting sleeve, means for connecting one end of the sleeve to a vibratory string, a first electrode of moderate mass and held in the sleeve near one end thereof, a second electrode of substantial mass within the sleeve, comminuted conducting material confined in the sleeve between the electrodes, and a non-resonant wrapping about the second electrode and supporting it within the sleeve.

75

41. A pulsator for purposes set forth, comprising a supporting sleeve, means for connecting one end of the sleeve to a vibratory string, a first electrode of moderate mass and held in the sleeve near one end thereof, a second electrode of relatively greater mass within the sleeve, comminuted conducting material confined in the sleeve between the electrodes, and a wrapping of non-resonant cord about the second electrode and supporting it within the sleeve.
